[57] **CLAIM**

The ornamental design for an icon for freehand drawing softkey display or the like, as shown and described.

DESCRIPTION

FIG. 1 is a face view of an icon for freehand drawing softkey display or the like showing our new design; FIG. 2A is an enlarged view of the left portion of FIG. 1;

FIG. 2B is an enlarged view of the central portion of FIG. 1;

FIG. 2C is an enlarged view of the right portion of FIG. 1;

FIG. 3 is a face view of an icon for freehand drawing softkey display or the like showing a modified form of our new design with alphanumeric information; FIG. 4A is an enlarged view of the left portion of FIG. 3;

FIG. 4B is an enlarged view of the central portion of FIG. 3;

FIG. 4C is an enlarged view of the right portion of FIG. 3;

The broken line showing of a partial half-tone display screen in FIGS. 1-4C and regions for alphanumeric information in FIGS. 1-2B is for illustrative purposes only and forms no part of the claimed design.
